UNITED STATES PATENT OFFICE.

THOMAS W. ELDER, JR., OF AVALON, PENNSYLVANIA, ASSIGNOR TO PRESSED STEEL CAR COMPANY, OF PITTSBURGH, PENNSYLVANIA, A CORPORATION OF NEW JERSEY.

TANK-CAR CONSTRUCTION.

1,226,647.

Specification of Letters Patent. Patented May 22, 1917.

Application filed September 23, 1914. Serial No. 863,159.

To all whom it may concern:

Be it known that I, THOMAS W. ELDER, Jr., a citizen of the United States, residing at No. 331 River avenue, Avalon, in the county of Allegheny and State of Pennsylvania, have invented certain new and useful Improvements in Tank-Car Construction, of which the following is a specification.

Heretofore the usual practice in tank car construction has been to mount the tank on a supporting underframe having center sills, and mounting the tank proper, which has generally been of a cylindrical shape, upon the underframe and above the center sills, and to prevent the tank from rolling sideways on the underframe, bands, which extend over the tank, are anchored in the underframe. To prevent the tank from shifting longitudinally relative to the underframe, either head blocks which serve as abutments for the ends of the tank have been secured to the underframe, or some form of anchorage located at or near the longitudinal center of the tank between the tank and the underframe have been used. For tanks of limited capacity such construction was in a general way unobjectionable, but with the increase in the size of the tank in modern tank cars, the center of gravity has been raised so far as to increase the danger of the car overturning, due to unevenness of tracks, centrifugal force when rounding curves at high speed and other well known causes. Further, tank cars now in general use are so constructed that the draft rigging and line of draft therethrough are below the tank, which has necessitated the raising of the center of gravity in large tanks with the resultant disadvantages and dangers.

An object of my invention is to provide a tank car in which the tank shall have a very large capacity and at the same time have a low center of gravity, whereby danger of overturning or derailing of the car in transit will be minimized, and also to provide a structure which will have the necessary rigidity and resistance to all strains which occur in service.

Another object of my invention is to provide a tank car construction in which the so called underframe is dispensed with, and to construct the tank and frame in such a manner as to produce a combined tank and

frame which is capable of taking care of the shocks due to buffing, pulling, etc., to which such cars are subjected in service.

A further object of my invention is to provide a tank car construction in which a considerable portion of the tank extends below the line of draft, and at the same time relieve the tank structure of any strains caused by buffing, pulling or other causes.

A further object of my invention is to so connect the tank and framing that the use of head blocks or some other form of fastening at or near the center of the car, to prevent or counteract longitudinal movement of the tank relative to the underframe, will be unnecessary, the tendency to such movement being resisted by the engagement of the head plates of the tank with the members of the framing.

A further object of my invention is to provide means whereby, shocks due to longitudinal wave motion of the contents of the tank, due to changes of speed of movement of the tank car, or sudden stoppages will be minimized.

A further object of my invention is to provide means by which the heater pipes, which are installed in a large number of tank cars, may be suspended from the frame member inside of the tank, thus avoiding the necessity of securing the pipes to the shell of the tank, with the attendant danger of loose rivets causing leakage of the contents of the tank.

In the accompanying drawings forming part of this specification and in which like reference numbers indicate like parts in all of the figures, Figure 1 is a side elevation of a tank car only a portion of the framing being shown; Fig. 2 is a sectional view taken on line 2—2 of Fig. 1, and Fig. 3 is a longitudinal vertical section taken on line 3—3 of Fig. 2. Fig. 4 is a longitudinal vertical section of the tank and the portion of the framing which passes through the tank, the end portions of the tank being of a modified form; Fig. 5 is a vertical cross section on line 5—5 of Fig. 4; Fig. 6 is a vertical cross section of the tank and framing taken on line 6—6 of Fig. 4; Fig. 7 is a cross section of the tank and framing and is intended to illustrate a system of bracing the framing to the tank when such bracing is found to be necessary, Fig. 8 is a section taken on

line 8—8 of Fig. 7, and Fig. 9 is a plan view of the car.

Referring now in detail to the drawings, 1 indicates the tank which may be of cylindrical or other suitable form, it being equipped with the usual dome 2, safety valves 3 and discharge valve 4. 5 indicates the head plates of the tank which may be dished in form as shown in the drawings. 10 6 indicates the framing of the car which is illustrated as consisting of two channel shaped members passing longitudinally through the tank and extending over the trucks to the end sill or striking plate 7 15 at the end of the car. These members 6 are equipped with the usual bolster member 8 which is located in suitable position thereon to coöperate with the truck bolster with which the truck is equipped. The frame 20 members 6 may pass through the head plates of the tank either at the diametral center of the tank or at any convenient and suitable distance therefrom. For the purpose of reinforcing the head plates 5 of the 25 tank, a metallic member 9 is secured thereto by means of rivets or other suitable fastening means. This member 9 is provided with openings 10 of suitable shape to accommodate and permit the frame members 30 6 to pass therethrough, and also with suitable gusset members 11 to stiffen the member 9 and to make it suitable for transferring the weight of the tank and its contents to the framing members 6. To prevent 35 vent leakage of the contents of the tank at the points where the frame members 6 pass through the member 9, electric welding or soldering may be resorted to to fill up any space that may remain between the 40 members 6 and the perforations 10 through which the members 6 pass, and rivets may also be used to secure the frame members 6 and the member 9 together at the points where they are in contact with each other. 45 If necessary the frame members 6 may be braced at points within the tank by suitable members 12.

It may here be explained that the expression frame members is used throughout this 50 description and the appended claims in a broad sense, and is intended to include not only a single but a multiple element which performs the general functions of a frame member longitudinally disposed and passing through the tank.

Fig. 4 shows a modification of my invention in which additional members 13 and 14 are added to make the tank more secure against accidental leakage. 13 indicates a 55 plate of substantially circular form which is riveted at its outer edge to the head plate of the tank. 14 indicates a member of similar form, the outer edge of which is riveted to the inner edge of the member 65 13. Member 14 is further furnished with

flange members 15 and 16, which may be welded to the frame members 6 at the points where they pass through or are in contact with the flanges 15 and 16.

17 indicates splash plates which may be of circular or other suitable form and which may be of a diameter equal to or somewhat less than the diameter of the tank. These plates 17 may or may not have perforations made therein as shown in Fig. 6, the purpose of these members being to prevent excessive longitudinal wave motion of the contents of the tank, due to sudden stoppages of the tank or to changes of speed of movement of the tank car, which causes severe shocks in the tank itself. 18 indicates the heater pipes which are shown as being suspended from the frame members 6, this being done to avoid perforation of the tank shell to accommodate rivets by which these heater pipes have generally been secured thereto. 19 indicates brace members for the purpose of bracing together the tank shell and the frame members 6. These members may be of any suitable number and distributed or disposed in any desired location inside of the tank, being secured to the frame members 6 preferably by means of gusset plates 20, and to the tank shell by means of gusset plates 21, and tank shell 95 stiffening members 22.

The bolsters 8, secured to the frame members 6, are braced together by means of diagonal members or side sills 28, which may extend from the ends 29 of the bolster to the metallic head plate member 9, and may be secured to the latter through the medium of the gusset member 11 in any suitable manner. The members 28 may be extended beyond the bolster to the end sill 105 7, and secured thereto in the usual manner. To further brace together the members of the end portion of the framing, additional diagonal braces 30 may be employed, extending from the bolster 8 to the end sill 110 7, and for the purpose of forming an end platform and additionally tying together the members of the end portion of the framing, the members 31 and 32, preferably in the form of flat plates, may be employed. 115

For the purpose of gaining access to the dome 2, safety valves 3 and discharge valve 4 of the car, and also to facilitate the passing of the trainmen from car to car, the car illustrated and described is equipped with the usual running boards 23, hand rails 24, ladders 25, steps 26, and grab irons 27.

It will be plain that the foregoing construction provides a tank car in which the center of gravity thereof is dropped to substantially the lowest possible point, while maintaining the necessary resistance and rigidity to both buffing and pulling stresses along the line of draft, as well as the neces- 130

sary resistance to lateral and twisting strains which would tend to strain or spring the joints of the tank and cause leakage. No material proportion of either the buffering,

5 pulling or twisting strains comes upon the joints of the tank plates, but is all taken care of by the frame members 6. The portion of the tank that extends below the line of draft is all utilized for load, the proportion of the load displaced by the interior 10 framing member being inconsiderable.

My invention is hereinabove set forth as embodied in one particular form of construction, but I do not limit it thereto or to less than all the possible forms in which the said invention as hereinafter claimed may be embodied and distinguished from prior devices for like purposes.

What I claim is:

20 1. In a tank car, the combination with a frame construction of a plurality of bolsters secured to said frame construction adapted to coöperate with trucks and a tank secured to said frame construction, the diametrical center line of said tank extending longitudinally of the car, the entire length of said tank extending between said bolsters, portions of said tank extending below said bolsters.

30 2. In a tank car, the combination of a plurality of bolsters adapted to coöperate with trucks, a tank, the entire length of said tank extending between and above and below the tops of said bolsters, the diametrical center 35 line of said tank extending longitudinally of the car.

3. In a tank car, the combination of a plurality of trucks and a tank, the entire length of said tank extending between and below the tops of said trucks, the diametrical center line of said tank extending longitudinally of the car.

4. In a tank car, the combination of a plurality of bolsters, adapted to coöperate with trucks, and a tank, the entire length of said tank extending between and below the tops of said bolsters, and the diametrical center line of said tank extending longitudinally of the car.

50 5. In a tank car, the combination of a tank and a continuous frame construction extending through and secured to the head plates of said tank, said frame construction extending a substantial distance beyond the ends of said tank and forming platforms.

6. In a tank car, the combination of a tank and a frame construction secured to the head plates of said tank and out of contact with the shell plates of said tank.

60 7. In a tank car, the combination of a tank and a frame construction extending longitudinally of the tank near its diametrical center, said frame construction being secured to the head plates of said tank, and bolsters secured to said frame construction

beyond the ends of said tank, said bolsters being adapted to coöperate with trucks.

8. In a tank car, the combination of a tank and a frame construction of flanged form extending longitudinally of the tank near its diametrical center, said frame construction being secured to the head plates of said tank, and being out of contact with the shell plates of said tank, and bolsters secured to said frame construction, said tank being of less length than the distance between said bolsters.

9. In a tank car, the combination of a tank and a frame construction, members of which frame construction extend through the head plates of said tank, and form platform supports at the ends of the car.

10. In a tank car, the combination of a tank and a flanged frame construction, members of which extend continuously through the head plates of said tank, and bolsters secured to said frame construction between the ends of said tank and the ends of said car, said bolsters being in the horizontal plane of said frame construction.

11. In a tank car, the combination of a tank and a frame construction, members of which extend through the head plates of said tank and from end to end of the car, and bolsters secured to said frame construction between the ends of said tank and the ends of said frame construction, the tops of said bolsters being in substantially the same horizontal plane as the top of said frame construction.

12. In a tank car, the combination of a tank and a frame construction, members of which extend continuously through the head plates of said tank and from end to end of the car, and bolsters secured to said frame construction between the ends of said tank and the ends of said frame construction, the tops of said bolsters being in substantially the same horizontal plane as the top of said frame construction.

13. In a tank car, the combination of a plurality of trucks, a tank having a portion of its length extending below the tops of said trucks and a framing passing through the interior of said tank, and forming the only support for the tank on the trucks.

14. In a tank car, the combination of a plurality of trucks, a tank having a portion of its length extending below the tops of said trucks and a framing passing continuously through the interior of said tank and forming the only support for the tank on the trucks.

15. In a tank car the combination of a tank and an interior framing passing through said tank and extending beyond its ends to form platform supports, and a bracing from said framing to said tank.

16. In a tank car, the combination of a tank and an interior channel shaped fram-

- ing passing through the head plates of said tank, and bracing from said framing to said tank, and bolsters secured to said frame construction between the ends of said tank and 5 the ends of said frame construction, the tops of said bolsters being in substantially the same horizontal plane as the top of said frame construction.
17. In a tank car, the combination of a 10 tank and an interior framing passing through the ends of said tank, said framing comprising a plurality of channel shaped members and splash plates secured to said members within and independent of said tank.
18. In a tank car, the combination of a 15 tank and an interior framing passing through said tank and splash plates secured to said framing and independent of said tank.
19. In a tank car, the combination of a 20 tank and an interior framing passing through said tank and splash plates secured to said framing and independent of the shell of said tank.
20. In a tank car, the combination of a 25 tank, and an interior framing passing through the ends of said tank and heater pipes suspended from said framing, but not 30 in contact therewith.
21. In a tank car, the combination of a 35 tank and an interior framing passing through the ends of said tank and heater pipes suspended from said framing and out 40 of direct engagement therewith and independent of the shell of said tank.
22. In a tank car, the combination with a 45 tank having substantially the same cross sectional area throughout its length, of a frame construction for supporting the entire weight of said tank, said frame construction passing through the head plates of said tank near its diametrical center.
23. In a tank car, the combination with 50 a tank, of a frame construction passing through the ends of said tank, heater pipes in said tank, and means carried by said frame construction for supporting said heater pipes below said frame construction.
24. In a tank car, a tank, a frame construction passing through the head plates of 55 said tank, heater pipes in said tank and a strap secured to said frame construction for supporting said heater pipes.
25. In a tank car, the combination with a tank and head plates, of a flanged load carrying member passing longitudinally through said tank and through said head plates, said tank having substantially the 60 same cross sectional area throughout its length.
26. In a tank car, the combination with a tank and head plates, of a continuous flanged load carrying member passing longitudinally 65 through said tank and through said

head plates, said tank having substantially the same cross sectional area throughout its length.

27. In a tank car, the combination with a tank and head plates, of a flanged load carrying member passing longitudinally through said tank and through said head plates near the diametrical center of said tank, said tank having substantially the same cross sectional area throughout its length.

28. In a tank car, the combination with a plurality of trucks, of a frame construction carried by said trucks, bolsters connected with said frame construction and adapted to coöperate with said trucks, the tops of said bolsters being in the same horizontal plane as the top of said frame construction, and a tank secured to and carried by said frame construction, said tank being of less length than the distance between said bolsters, the diametrical center line of said tank extending in a direction longitudinally of the car.

29. In a tank car, the combination with a plurality of trucks of a frame construction carried by said trucks, bolsters connected with said frame construction adapted to coöperate with said trucks and a tank carried by said frame construction, said tank extending above and below said frame construction, and being of less length than the distance between said bolsters.

30. In a tank car, the combination with a plurality of trucks, of a frame construction carried by said trucks and a tank irremovably carried by said frame construction, the entire length of said tank being of less length than the distance between said trucks, the diametrical center line of said tank extending longitudinally of the car.

31. In a tank car, the combination with a plurality of trucks, of a frame construction carried by said trucks, and a tank carried by said frame construction, the entire length of said tank being of less length than the distance between said trucks, and having a portion of its entire length extending below the tops of said trucks, the diametrical center line of said tank extending longitudinally of the car.

32. In a tank car, end sills, a frame member extending from end sill to end sill, bolsters secured to said frame member and a tank carried by said frame member of less length than the distance between said bolsters, said frame member passing through said tank.

33. In a tank car, end sills, frame members extending from end sill to end sill, bolsters secured to said frame members, a tank of less length than the distance between said bolsters carried by said frame members, and side sills connected with said bolsters and tank.

34. In a tank car, end sills, flanged frame

members extending from end sill to end sill, bolsters connected with said frame members, and a tank carried by said frame members, said tank being of less length than the distance between said bolsters and a portion of the entire length of said tank extending below the tops of said bolsters, the diametrical center line of said tank extending longitudinally of the car.

- 10 35. In a tank car, a plurality of trucks, a frame member carried by said trucks, and a tank of less length than the distance between said trucks carried by said frame member, a portion of the entire length of said tank extending below the tops of said trucks, the diametrical center line of said tank extending longitudinally of the car.
36. In a tank car, the combination with a tank, of a load carrying member extending therethrough, wheels supporting said load
- 15
- 20

carrying member, said tank extending longitudinally only between said wheels.

37. In a tank car, the combination with a tank, of a load carrying member extending therethrough, wheels supporting said load 25 carrying member, said tank having a length less than the distance between said wheels.

38. In a tank car, the combination with a tank, of a load carrying member extending therethrough, wheels supporting said load 30 carrying member, said tank having a length less than the distance between the inner faces of said wheels.

In testimony whereof I affix my signature in presence of two witnesses.
